(57) **CLAIM**

The ornamental design for an automobile and toy replica thereof, as shown and described.

DESCRIPTION

FIG. 1 is a right-front, perspective view of an automobile and toy replica thereof of my new design, the left, front perspective view being a mirror image thereof, with the exception of the windshield wiper assemblies which are not symmetric;

FIG. 2 is a right-rear, perspective view of my new design, the left, rear perspective view being a mirror image thereof, with the exception of the windshield wiper assembly which is not symmetric;

FIG. 3 is a right-side view of my new design, the left-side view being a mirror image thereof, with the exception of the windshield wiper assemblies which are not symmetric;

FIG. 4 is a front view thereof;

FIG. 5 is a rear view thereof; and,

FIG. 6 is a top view thereof.
